UNITED STATES PATENT OFFICE.

JOHN W. CURRY, OF CINCINNATI, OHIO.

HARNESS-TRACE.

1,097,214.

Specification of Letters Patent. Patented May 19, 1914.

Application filed March 2, 1912. Serial No. 681,165.

To all whom it may concern:

Be it known that I, JOHN W. CURRY, a citizen of the United States, residing at Cincinnati, in the county of Hamilton and State of Ohio, have invented certain new and useful Improvements in Harness-Traces, of which the following is a specification.

My invention relates to improvements in harness traces.

One of its objects is to provide a trace of less weight, stronger, more flexible, and of longer life as regards wear, weather, and similar conditions, than leather traces heretofore commonly used.

Another object is to provide improved means to increase the strength of the trace longitudinally, or in the direction of greatest strain.

Another object is to provide improved means to attach the body of the trace and its terminal or eye members together to resist the strains to which such joints are liable to be subjected.

My invention further comprises certain details of form, combination and arrangement, all of which will be fully set forth in the description of the accompanying drawings, in which—

Figure 1 is a perspective view of a trace embodying my improvements. Fig. 2 is a plan view of one end of a trace illustrating a modification of Fig. 1. Fig. 3 is an enlarged section on line $x-x$ of Fig. 2. Fig. 4 is a side elevation of one form or rivet preferably employed. Fig. 5 is a sectional detail on line $v-v$ of Fig. 3. Fig. 6 is a side elevation illustrating another modification.

The accompanying drawings illustrate the preferred embodiments of my invention.

The traces forming the subject-matter of my invention are designed to be employed in pairs as connections between the harness and the vehicle, and through which the strain necessary to draw or propel the vehicle is to be transmitted.

Each trace comprises a body portion A of woven or textile material, such as cotton for instance, and terminal members B and B' at opposite ends provided with hooks or eyes by means of which the traces may be readily attached at one end to the harness and at the opposite end to the vehicle. The terminal members B, B', are preferably of metal, and as illustrated are provided with eyes 2, formed from a piece of sheet metal by bending it into a loop so that its opposite ends

will embrace opposite faces of one end of the member A. The loops are preferably formed with a short shank 3 and a long shank 4, and said shanks united together upon the end of the member A by means of rivets 5 having cylindrical shanks 6 and heads 7 and 8 at the outer faces of the shanks 3 and 4, and serving primarily to lock the two shanks 3 and 4 together to complete the eye of said terminal member, and incidentally to lock the end of member A between said shanks where it is protected from fraying or unraveling.

In addition to the rivets 5, I preferably employ a series of rivets 9 having split or bifurcated shanks 10 and heads 11. The shanks 10 are inserted through perforations in the extended portion of shank 4 and through the end of member A in such manner as to divide and pass between its component fibers or threads instead of severing the same. The projecting ends of the shanks 10 are then turned down or clenched as indicated in Fig. 5, and may if desired be forced down into the fiber so as to be flush with the face of member A. The rivets 9 are mainly relied upon to transmit the strain and to prevent the members B, B', from parting company with member A under strain.

In order to increase the strength of member A lengthwise or in the direction of greatest strain, and particularly at the points where the member A is secured by the rivets to the members B, B', I provide a number of lines of stitches 12 of the lock stitch type running longitudinally of member A and inserted under tension preferably to sink said stitches into the fiber of member A so as to be flush with or below the faces of member A. In Fig. 1 the lines of stitches extend the full length of member A, while in the modification Fig. 2 the lines of stitches 12' are extended only through the ends of member A' where said member is to be attached to its terminal members. In Fig. 2 a section 14 of the eye of member B has been cut away to receive a hook or eye from the harness or vehicle.

In the modification Fig. 6 a piece of canvas or like material 15 is inserted with the end of member A² and locked in place by the rivets 5', and its free end allowed to hang as indicated at 16 in dotted line until after the rivets 9 are inserted and clenched, after which it is drawn as a finish over the

clenched ends of the rivets 9 and secured to member A² by a line of stitches 17.

The textile material of members A is treated with materials suitable to render it practically water-proof to protect the fiber from moisture and dampness, and from the adhesion of mud or other substance with which the traces are liable to come in contact.

10 The article herein illustrated and described is capable of considerable modification without departing from the principle of my invention.

Having described my invention, what I claim is:

1. A trace comprising a body of woven cellulose textile material having a plurality of lines of stitching evenly distributed and extending longitudinally thereof to increase 20 the strength of said body portion in the direction of its length, terminal connecting members having shanks embracing opposite faces of the respective ends of said body portion, and a plurality of rivet members 25 evenly distributed over said overlapping portions of the trace ends and the terminal connecting members and passing through said shanks and between the fibers of said body portion to unite said terminal members to said body portion to resist strains longitudinally of said trace.

2. A trace comprising a body portion composed of a unitary web of textile material having a selvage at each edge, and terminal 35 connecting members having shanks united to one face of the respective ends of said body portion by a multiplicity of rivet members passing through said shanks and between the fibers of said body portion.

40 3. A trace comprising a body portion composed of a unitary web of textile material having a selvage at each edge, and terminal connecting members having shanks united to one face of the respective ends of said body 45 portion by a multiplicity of rivet members distributed uniformly over the area of the overlapping portions of the trace ends and the terminal connecting members and passing through said shanks and between the 50 fibers of said body portion.

4. A trace comprising a body portion composed of a unitary web of woven textile material having a selvage at each edge, a plurality of lines of stitching evenly distributed 55 and extending longitudinally thereof to increase the strength of said body portion lon-

gitudinally, and terminal connecting members having shanks united to one face of the respective ends of said body portion by rivet members passing through said shanks 60 and between the fibers of said body portion to unite said terminal members to said body portion.

5. A trace comprising a body portion composed of a unitary web of woven textile 65 material having a selvage at each edge and a plurality of lines of stitching evenly distributed and extending longitudinally thereof at opposite ends to reinforce the ends of said body portion, and terminal connecting 70 members having shanks united to one face of the respective ends of said body portion by rivet members distributed evenly over said overlapping portions of the trace ends and the terminal connecting members and 75 passing through said shanks and between the fibers of said body portion to unite said terminal members to said body portion to resist strains longitudinally of said trace.

6. A trace comprising a body portion 80 composed of a unitary web of woven fibrous cellulose material having lines of stitching evenly distributed and extending longitudinally thereof, and metal terminal connecting members each having shanks united to 85 opposite sides of the ends of said body portion, said shanks and body portion being secured together by rivet members passing through said shanks and body portion.

7. A trace comprising a body portion 90 composed of a unitary web of woven cellulose textile material having a selvage at each edge and lines of lock stitching evenly distributed and extending longitudinally thereof to increase the strength of said body portion 95 longitudinally, and metal terminal connecting members having shanks united to one face of the respective ends of said body portion by a multiplicity of rivet members distributed uniformly over an extended area 100 of said overlapping portions of the trace ends and the terminal connecting members and passing through said shanks and between the fibers of said body portion to unite 105 said terminal members to said body portion to resist strains longitudinally of said trace.

In testimony whereof I have affixed my signature in presence of two witnesses.

JOHN W. CURRY.
